UNITED STATES PATENT OFFICE

2,441,495

BEARING

Arthur L. Lee, Upper Arlington, Ohio, assignor to
 The Jeffrey Manufacturing Company, a corporation of Ohio

Original application April 6, 1945, Serial No.
 586,979. Divided and this application June 25,
 1946, Serial No. 679,302

2 Claims. (Cl. 308—187.1)

1

This invention relates to a mining machine. An object of the invention is to provide a mining machine with a readily removable bearing block which holds a rotor shaft bearing and is preferably held against rotation by automatically acting retention means.

Other objects of the invention will appear hereinafter, the novel features and combinations being set forth in the appended claims.

In the accompanying drawings,

Fig. 1 is a side elevational view of the shortwall type mining machine herein disclosed which incorporates the features of my invention, the cutter bar being shown cut short;

Fig. 2 is an enlarged partial side elevational view, with parts broken away and shown in vertical section;

Fig. 3 is an enlarged sectional view showing particularly the structure and mounting of the generally cylindrical rotor bearing block of the mining machine motor; and

Fig. 4 is an elevational view taken on the line 4—4 of Fig. 3, with the shaft and locking pin shown in section.

This application is a division of my application Serial No. 586,979, filed April 6, 1945, entitled Mining machine.

Referring to the drawings, it will be seen that the machine includes a main frame 40 which in practice is preferably formed of two substantially independent frames including a forward motor frame or section 41 and a rearward machinery frame or section 42, the two frames or sections 41 and 42 being removably connected together as by machine screws or bolts.

Removably attached to the rear end of the machinery frame or section 42 is a gummer, bugduster or cuttings removing mechanism 43 which may be optionally employed or omitted. Extending forwardly from the motor frame or section 41 is a kerf-cutting mechanism 44 including an elongated cutter bar 45 which is of substantially standard construction except for the rear end portion and upon which there is mounted an endless cutter chain 46 provided with removable and reversible cutter bits 47.

As is well known, the shortwall type of mining machine is adapted to be fed as a unit over the mine floor while cutting a kerf, the kerf being cut by first sumping the cutter bar into the solid coal and then feeding the machine laterally or across the coal face, all the while the kerf-cutting mechanism 44 is in operation.

To effect the feeding of the mining machine as a unit, both at a kerf-cutting speed and at a

2

handling or higher speed and in reverse directions, the machine includes a pair of feed cable or rope drums on opposite sides thereof mounted on aligned horizontal axes, one of which drums is seen at 48 in Fig. 1 of the drawings.

The mining machine is adapted to rest on and slide over the mine floor when in operation and the supporting surfaces of the machine are provided largely by four spaced hydraulic piston 10 jacks or motors, there being two at the rear designated 57 and two at the front designated 58. These hydraulic jacks provide for adjusting the elevation of the cutter mechanism 44 or, in other words, the effective height of the machine and 15 also provide for adjusting the inclination or tilt thereof on right angularly related axes relative to a horizontal plane.

Extending from the motor section 41 into the machinery section 42 is the end of a drive shaft 20 59. Keyed adjacent the end of the shaft 59 is a pinion 61 which meshes with a larger pinion 62 keyed to a shaft 63, the gears 61 and 62 constituting elements of a gear train which leads to the drive mechanism for the cutter chain 46 25 and for the feed drums, one of which is seen at 48, as well as for the bugduster 43, all as disclosed in full detail in my above identified parent application.

Within the enclosure provided by the casting 30 frame or housing 41 is a rotor or armature of the mining machine driving motor. The frame 41 is primarily of magnetic material, such as iron, to provide a magnetic path for the flux of said driving motor. The rotor or armature is mounted 35 on a hollow or tubular rotor or armature shaft 156 which at its rear is supported on a roller bearing 157 which is supported in a generally cylindrical bearing block, cartridge or retainer 158 which is mounted in a cup 159 formed integral with the frame 41. The block or cartridge 158 is provided with a pair of oil seal piston rings 160 which cooperate with the inner cylindrical surface of the cup 159.

Bearing block or cartridge 158 is slidable with 45 the armature or rotor, the shafts 59 and 156 and the bearing 157, together with pinion 61 and the inner race of a bearing (not shown) which supports the rear end of shaft 59 and a grooved oil seal ring 162, so that all of these parts can be 50 removed by sliding them forwardly through the front of the casing or housing 41 after removing a front cover plate 161 and elevating the front end with respect to the cutter bar 45 by expanding front jacks 58.

55 The grooved seal ring 162 cooperates with the

adjacent surface formed by a hole in the forward vertical wall of the frame 42, through which the pinion 61 extends and thus reaches the machinery or gearing within said enclosure or compartment 42. No attempt is made to provide an oil tight seal at this place.

The structure of the cartridge or bearing block 158 and associated mechanism provides an important part of my invention and allows for the ready removal of the rotor or armature, together with its easy re-insertion. This is also described in my parent application and in my co-pending application, Serial No. 679,303, filed June 25, 1946.

To this end, the cup 159 is tapered at its inner right hand end to guide the block or cartridge 158 into place and to compress the piston rings 160. Furthermore, it is desirable that the block or cartridge 158 be held against rotation to prevent damage to it, and I have provided automatic means to do this which at the same time will provide for its ready insertion without requiring accurate alignment. The rearward outer cylindrical surface of the block 158 is provided with a plurality of spaced notches 163, any one of which is adapted to receive a locking pin 164 which is urged into an aligned notch 163 by a spring 165. The pin 164 and spring 165 are carried in an appropriate pocket formed in the machinery frame 42, and the pin 164 extends not only into any one of the notches 163, but also into a notch 166 formed in the cup 159.

When the block or cartridge 158 is inserted into the cup 159, it may be that none of the notches 163 is in alignment with the pin 164. If this is true, the pin 164 will merely be depressed against the spring 165 and when the unit is placed in operation, if there is any creepage between the block or cartridge 158 and the cup 159, a notch 163 will come into alignment with the pin 164 and it will snap into said notch, thereby holding the block or cartridge 158 against rotation with respect to the cup 159.

The block or cartridge 158 is provided with a pair of adjacent oil seals 182 which prevent entrance of oil into the interior of the motor cas-

ing. Any small leakage which may get by the seals 182 is drained by a passageway 183, which includes a peripheral groove 184 about the outer surface of the block 158 and between the two piston rings 160.

Obviously those skilled in the art may make various changes in the details and arrangement of parts without departing from the spirit and scope of the invention as defined by the claims 10 hereto appended, and I therefore wish not to be restricted to the precise construction herein disclosed.

Having thus described and shown an embodiment of my invention, what I desire to secure by 15 Letters Patent of the United States is:

1. A mining machine including a frame, a motor having a rotor shaft, means for supporting said rotor shaft in said frame including a cup formed in said frame, a bearing block slidably 20 carried in said cup, piston rings carried by said block and cooperating with said cup to form an oil seal, an oil drain groove between said rings, and a bearing supporting said rotor shaft from said bearing block.
- 25 2. A mining machine including a frame, a motor having a rotor shaft, means for supporting said rotor shaft in said frame including a cup formed in said frame, a bearing block slidably carried in said cup, piston rings carried by said 30 block and cooperating with said cup to form an oil seal, and a bearing supporting said rotor shaft from said bearing block.

ARTHUR L. LEE.
